UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A SHIN-PIECE FOR PLOWS.

SPECIFICATION forming part of Design No. 28,333, dated March 1, 1898.

Application filed December 31, 1897. Serial No. 665,252. Term of patent 14 years.

To all whom it may concern:

Be it known that I, GEORGE W. REAM, a citizen of the United States, residing at Canton, in the county of Stark and State of Ohio, 5 have invented and produced a new and original Design for a Shin-Piece, of which the following is a specification.

In the accompanying drawings, Figure 1 is a side elevation of my new design. Fig. 2 10 shows the opposite side in elevation. Fig. 3 is a plan view looking down upon it, and Fig. 4 is a section on line 4 4 of Fig. 1.

The leading feature of the design is in the configuration or outline and in the surface 15 configuration of the rear side. The front line

A extends in a continuous curve from top to bottom, while the bottom line B is above the lower end, leaving a projection C. The rear

line is formed on a partial straight line to the point D and then curves inwardly, as shown 20 at E, to the upper end. From the curved line A, forming the edge, the shin-piece recedes at an angle to the surface F, as shown at G, Figs. 3 and 4, and this part G terminates in a shoulder, where it joins the web H, as shown 25 in Fig. 4.

I claim—

The design for a shin-piece as herein shown and described.

In testimony whereof I affix my signature 30 in presence of two witnesses.

GEORGE W. REAM.

Witnesses:

W. H. CAVNAH,
Jos. H. MILLER.
